UNITED STATES PATENT OFFICE.

ELMER F. RAMSBERGER, OF PHILADELPHIA, PENNSYLVANIA.

DESIGN FOR A SEAL FINGER-RING.

51,047.

Specification for Design. Patented July 17, 1917.

Application filed April 4, 1917. Serial No. 159,790. Term of patent 14 years.

To all whom it may concern:

Be it known that I, ELMER F. RAMSBERGER, a citizen of the United States, residing at 6113 Ross st., Germantown, Philadelphia, Pa., in the county of Philadelphia and State of Pennsylvania, have invented a new, original, and ornamental Design for Seal Finger-Rings, of which the following is a specification, reference being had to the accompanying drawing, forming part thereof.

The figure is a perspective view of a seal finger ring, showing my new design.

I claim:

The ornamental design for a seal finger ring, as shown.
